UNITED STATES PATENT OFFICE.

JOHN EDSON SWEET, OF SYRACUSE, NEW YORK.

STEAM-SEPARATOR.

SPECIFICATION forming part of Letters Patent No. 624,575, dated May 9, 1899.

Application filed September 17, 1896. Serial No. 606,130. (No model.)

To all whom it may concern:

Be it known that I, JOHN EDSON SWEET, a citizen of the United States of America, residing at Syracuse, in the county of Onondaga and State of New York, have invented certain new and useful Improvements in Steam-Separators; and I do hereby declare the following to be a full, clear, and exact description of the invention, such as will enable others skilled in the art to which it appertains to make and use the same.

Reference is made to the accompanying drawings, forming a part of this specification, in which—

15 Figure 1 is a cross-section of my improvement. Fig. 2 is a side elevation of a portion of the same in place in a marine boiler such as is in use in the United States Navy. Fig. 3 shows in longitudinal section a modified form 20 which can be used in an extension from the boiler in cases where it is not desirable or practicable to introduce the separator into the boiler itself, and Fig. 4 is a cross-sectional view of the same.

25 Like letters of reference refer to like parts upon the drawings.

The details of the several parts will be described below.

My invention relates to improvements in 30 steam-separators for marine boilers; and it consists in a modification of my invention in separators patented January 8, 1895, No. 532,296, whereby it is especially adapted to the purpose above mentioned.

35 In marine boilers it is quite common to have a simple form of separator, known as a "dry-pipe," extending along the top of the boiler, in the steam-space thereof, with perforations in the top of the pipe intended to take the 40 steam from the driest part of the space where it is least impregnated with free moisture. Experience, however, shows that under the motion of a vessel at sea the water in the boiler can by no such means be kept out of the dry-pipe, but under the rolling action of the waves is often thrown to the top of the boiler and deflected upon the dry-pipe and enters the 45 perforations with the steam. My invention is designed to supply a remedy for this defect 50 and furnish a separator which may be introduced and used within the boiler or an extension thereof with the same facility as the

dry-pipe and yet be free from the aforesaid disadvantages.

In my former patent, No. 532,296, I have shown and described a separator located in a vertical exit-pipe from the boiler or an enlargement thereof, consisting, in brief, of a frusto-conical shell of perforated sheet metal so located with respect to the steam-inlet pipe 60 that any water entering with the steam will be caught on the perforated surface thereof and retarded and eventually find its way to the bottom of the outer shell and be there withdrawn, while the more mobile and volatile particles of steam seek their exit under pressure by an upward diversion, and thus become disentangled and leave the accompanying moisture behind and emerge in a comparatively dry state. My present device 70 is constructed on similar principles, but horizontally disposed and arranged, so as to be readily introduced through a manhole into a marine boiler or an extension thereof in the position and with the functions heretofore 75 pertaining to the dry-pipe. The perforations on the top of the dry-pipe are dispensed with, and a provision is made whereby the water from the "swash" of the boiler is more effectively prevented from entering the separator. 80

In the drawings, A is a segmental pipe corresponding to the former dry-pipe, but open at the bottom.

B is a metallic trough or its equivalent under and covering the opening in A, extending 85 upward along the sides of the pipe A, with a narrow passage c between and firmly and detachably secured to the latter by spacing-bolts f, nuts h, and sleeves i, as shown, or in any other suitable and workmanlike manner. 90 The upper edges of the said trough are furnished with outturned lips b, and a corresponding outturned lip a is supplied above each, leaving a narrow slit or passage-way C between the two, extending lengthwise of the 95 separator, of a dimension of opening corresponding to the size of the outlet. This slit is the entrance-passage for the steam and may obviously be employed on one or both sides of the pipe with similar results. The 100 purpose of the outturned lips is to deflect and ward off from entrance any water which may be splashed up or deflected down upon the separator. Within the trough B is secured

5 a perforated sheet-metal lining or sieve D, passing downward along the sides thereof, as shown, and turned sharply upward at the lower edge in a curved deflection g just below the edge of the open pipe A. The two edges meet and are joined in the center, as at d, and, if desired, a partition-plate e is secured in place at this point to arrest the water from either side and prevent its going 10 through the perforations on the other side.

15 E E are the outlet-pipes, which drain the accumulating water from the separator into the boiler. They terminate below the water-line thereof, and their lower terminals are protected by suitable check-valves. (Not shown, as their function is well known.)

20 M is a section of a portion of the shell of a marine boiler.

25 n n are the hangers for securing the separator-pipe.

30 The operation is as follows: Steam enters freely through the inlet slits or passages C, whence it passes along down through the passages c, over the perforated linings or sieves D, and is deflected upward into the steam-exit pipe A. In its passage the water in the steam is forcibly thrown against the said sieves and through the perforations thereof, where it is entrapped by its own comparative 35 inertia and the surface attraction exerted by the extended metal surface and is thus partitioned away from the more mobile current of steam to be withdrawn through the educt-pipes E E.

35 In the modification shown in Figs. 3 and 4 A' is a horizontal extension from the boiler, in which the pipe A is located. The lateral inlet-slits C in this modification are dispensed with, since the separator is in this case protected from the swash of the water in the 40 boiler. The steam enters through the passage C' into the space or chamber F, surrounding the upper portion of the separator-pipe A, whence it finds its way through the narrow passages c c, as before, passing over 45 the sieves or lining-plates D, the steam being deflected, as before, into the interior of the pipe A and thence passing out through the exitway I, while the water, being thrown 50 forcibly against the sieves D, passes through them and is held in the chamber below and thence drawn off to be returned to the boiler, the lower segment of the pipe A' in this case constituting the trough B and serving the 55 functions thereof. G is the usual water-glass gage.

I claim and desire to secure by Letters Patent—

1. A steam-separator for location within the steam-space of a boiler, consisting of a 60 horizontal pipe having a long narrow steam-inlet opening in the side or sides thereof, and outturned lips above and below said opening, whereby water is deflected away from the same, substantially as specified. 65

2. In a steam-separator, a horizontal pipe, open at bottom, in combination with a trough overlapping the same from the bottom to about midway of the sides, leaving downwardly-inclined steam-inlet spaces between 70 the sides of the pipe and the overlapping trough, guarded by outturned lips, substantially as shown and described.

3. In a steam-separator, a horizontal pipe, open at bottom, in combination with an overlapping trough, spaced to afford steam-passages, and the outturned lips a b, forming guarded steam-inlets at the sides of the separator, substantially as shown and described. 75

4. In a steam-separator, the combination of 80 the horizontal pipe, open at bottom, the overlapping trough spaced to afford passages between the same, the outturned lips a b, forming guarded steam-inlet slits, and perforated linings or sieves secured to the said trough 85 within the said passages, substantially as shown and described.

5. In a steam-separator, the combination of 90 the horizontal pipe A, open at bottom, the trough B, detachably secured thereto and affording steam-spaces c, outturned lips a b, forming lateral guarded steam-inlets C, perforated sieve-linings D, having upturned deflections g, joined in the center, and outlet-pipes E, substantially as shown and described. 95

6. The herein-described improvement in steam-separators, consisting of a horizontal member double-walled and spaced at the sides, provided with lateral steam-inlet slits guarded by outturned lips a b, perforated metallic sieve-linings secured within the double-walled spaces, having upturned deflecting lower edges, a central partition e, and outlet-pipes E, all substantially as shown and described and for the purpose specified. 100 105

In testimony whereof I affix my signature in presence of two witnesses.

JOHN EDSON SWEET.
